UNITED STATES PATENT OFFICE

VITO ORAZIO RAIMONDI, OF CHICAGO, ILLINOIS

NOVELTY TOP

Application filed September 13, 1929. Serial No. 392,290.

This invention relates to a novelty top, and an object is the provision of a simple yet durable top provided with a plurality of wings or leaves which are adapted to open when the top is spun and strikes a surface. As a more specific object, the invention aims to provide a novelty top having the external appearance of an ordinary top but being formed of a shell-like structure whereby a plurality of wings are automatically opened when the top is put in operation, thus providing a very attractive and engaging novelty top for children.

Other objects will appear hereinafter.

15 The invention consists in the combinations and arrangements of parts hereinafter described and claimed.

The invention will be best understood by reference to the accompanying drawings forming a part of this specification, in which :

Fig. 1 is an elevational view of the device in closed position;

Fig. 2 is a vertical sectional view of the device in closed position;

Fig. 3 is a vertical sectional view showing the foldable leaves in partially open position immediately after impact of the device with the surface upon which it is to revolve;

Fig. 4 is a vertical sectional view of the device with the wings fully open, as in spinning position;

Fig. 5 is a horizontal sectional view, taken substantially on the line 5—5 of Fig. 1; and

Fig. 6 is a detailed plan view of the retaining disk.

The preferred form of the device illustrated in the drawings comprises a supporting stem 9, the upper portion of which is polygonal in cross-section, and adapted to make a sliding fit in a sleeve member 10 having a bore corresponding in cross-sectional outline with that of the stem 9. The upper end of the stem member 9 is internally threaded to receive the threaded extension 11 depending from the cap support 12. Carried by the cap support 12 and preferably secured thereto by spot welding or equivalent method, is a dome-shaped hood 13, the outer peripheral edge of which is turned upwardly and inwardly and then down-

wardly to provide an annular flange 14 and an annular groove 15.

Threaded upon the lower extremity of the sleeve 10 is a wing support 16, which is provided with an annular groove around the upper periphery for the reception of a ring 17 which is held in place by disk member 18. A plurality of wings 19 are pivotally mounted upon the ring 17. As shown in Fig. 5, the wings 19 taper inwardly and at the inner edge each wing is turned to form a socket which is engaged by the ring 17, as shown in the several views, and in order to enable the wings to be folded upwardly, the disk 18 has peripheral notches 20 disposed adjacent the respective socket portions of the wings. Downward movement of the wings is limited by a shoulder 21 provided on the support 16, and the latter has a relatively large bore for receiving a compression spring 22 which surrounds a portion of stem 9 and is disposed between the lower extremity of sleeve 10 and the spinning head 23 provided on the lower end of stem 9. The free ends of the wings 19 are preferably slightly flared outwardly as at 24 and in closing make snap engagement with the annular groove 15 of the hood 13, in which position they are held as shown in Fig. 2, by means of the compression spring 22 which is of sufficient strength to maintain the wings normally in closed position, but to yield under the weight of the wing support 16 and the sleeve 10 upon the impact of the spinning head 23 with a surface 25 upon which the top is thrown.

Support 16 has a reduced annular groove portion 26 within which a string is wound in operating the top. The top is then thrown in the usual manner, by which operation it is spun, and upon impact with the surface, stem 9 and consequently hood 13 are elevated relative to the sleeve 10 and connected parts whereby the device assumes the position shown in Fig. 3. The weight of the wings 19, together with the centrifugal force, throw the wings outwardly to the position shown in Fig. 4, in which position the top is maintained until the momentum is decreased to the point where it no longer remains erect.

As an additional feature of ornamentation

and attractiveness, each wing preferably carries upon its inner surface a miniature running horse 27 or similar device, and the horses are preferably placed to face in the same direction. For re-use, wings 19 are merely folded upwardly and snapped into the position shown in Figs. 1 and 2, where they are maintained until the next operation by the compression spring 22.

10 It will be understood that while stem 9 and sleeve 10 are movable longitudinally relative to each other, relative rotary motion is prevented by reason of the polygonal cross-sectional outline.

15 While I have illustrated and described the preferred form of construction for carrying my invention into effect, this is capable of variation and modification without departing from the spirit of the invention.

20 I, therefore, do not wish to be limited to the precise details of construction set forth, but desire to avail myself of such variations and modifications as come within the scope of the appended claims.

25 Having thus described my invention, what I claim as new and desire to secure by Letters Patent is:

1. A device of the class described comprising a stem provided with a spinning 30 head, a sleeve member rotatable with said stem and slidably relative thereto, a plurality of wings pivotally mounted upon said sleeve member, a hood mounted upon said sleeve and adapted to engage said wings 35 when in closed position, and yieldable means for normally maintaining said wings in closed engagement.

2. A device of the class described comprising a stem having a spinning head, a sleeve 40 member slidably mounted upon said stem, a wing support carried by said sleeve member, a plurality of wings pivotally mounted upon said wing support, and means for engaging said wings to normally maintain same in closed position and adapted to release said wings upon impact of said spinning head with a surface.

3. A device of the class described comprising a stem having a spinning head, a sleeve 50 member slidably mounted upon said stem, a wing support carried by said sleeve member, a plurality of wings pivotally mounted upon said wing support, and a hood member carried by said stem and adapted to engage 55 and normally maintain said wings in closed position, and also adapted to release said wings upon impact of said spinning head with a surface.

4. A device of the class described comprising a stem having a spinning head, a sleeve member slidably mounted upon said stem, a wing support carried by said sleeve member, a plurality of wings pivotally mounted upon said wing support, a hood 65 member carried by said stem and adapted

to engage and normally maintain said wings in closed position, and also adapted to release said wings upon impact of said spinning head with a surface, and spring means adapted normally to maintain said wings engaged with said hood.

In testimony whereof I have signed my name to this specification.

VITO ORAZIO RAIMONDI.
